[57] CLAIM

The ornamental design for a handle for a fishing device,
as shown and described.

DESCRIPTION

FIG. 1 is a side elevation view of a handle for a fishing device, showing my new design;

FIG. 2 is a top plan view thereof;

FIG. 3 is an end view, from the left side as shown in
FIG. 1;

FIG. 4 is an end view, from the right side as shown in
FIG. 1; and

FIG. 5 is a bottom view.

The hidden side is a mirror image of FIG. 1.

FIG. 2

FIG. 3

FIG. 4

FIG. 1
